UNITED STATES PATENT OFFICE.

ISRAEL V. MYERS, OF KANSAS CITY, MISSOURI.

RECLINING-CHAIR.

1,231,414.

Specification of Letters Patent. Patented June 26, 1917.

Application filed June 6, 1914. Serial No. 843,440.

To all whom it may concern:

Be it known that I, ISRAEL V. MYERS, a citizen of the United States, residing at Kansas City, in the county of Jackson and State of Missouri, have invented a certain new and useful Improvement in Reclining-Chairs, of which the following is a specification.

My invention relates to improvements in 10 reclining chairs.

The object of my invention is to provide a reclining chair, which is simple in construction, is strong and durable, which may be easily and quickly operated by an unskilled person, and which may be adjusted to various positions to suit the convenience of the operator, or the occupant of the chair.

The novel features of my invention are hereinafter fully described and claimed.

20 In the accompanying drawings, which illustrate the preferred embodiment of my invention,

Figure 1 is a side elevation of my improved chair with the back and arms shown in the upright position.

Fig. 2 is a bottom view, showing the back and foot rest in the horizontal position, the legs being shown in horizontal section.

Fig. 3 is a vertical sectional view, showing 30 the back and arms in the upright position.

Fig. 4 is a vertical sectional view, showing the arms in the upright position and the back and foot rest in the horizontal position.

35 Similar reference characters designate similar parts in the different views.

The seat comprises a horizontal frame 1 having secured to it the front legs 2 and the back legs 3, and having mounted on it a 40 cushion 4.

Two arms 5 are secured by hinges 6 having horizontal pivots to opposite sides of the frame 1.

Hinged to the frame 1 by means of a horizontal bolt 7 is a back provided with a frame 8, through which the bolt 7 extends, and which is adapted to support a detachable cushion 9, which on its rear side and near its upper end is provided with hangers 50 10, which are adapted to be supported by the upper edge of the frame 8, as best shown in Fig. 3. As shown in dotted lines in Fig. 4, the cushion 9 may be adjusted so as to

about against the seat cushion 4 when the back is horizontally disposed. 55

The back is adapted to be swung from the upright positions shown in Figs. 1 and 3 to the substantially horizontal positions shown in Fig. 4. For reliably supporting the back in the last named position, I provide two extensible braces, each consisting of a tube 11, the upper end of which is pivoted to the frame 8 near the middle and adjacent to one side thereof. In each tube 11 is slidably mounted a rod 12, the lower end of 60 which is pivoted to the adjacent rear leg 3. 65

When the back is in the horizontal position shown in Fig. 4, the braces comprising the tubes 11 and the rods 12 are fully contracted and firmly support the back in that 70 position.

Secured to the under side of the frame 1 are two yielding buffers 13, preferably of soft rubber, and which are adapted to be respectively struck by two downwardly extending arms 14, with which the lower end 75 of the frame 8 is provided, as is shown in Figs. 2 and 4.

The buffers 13 are arranged to receive the impact of the arms 14 just prior to the back 80 reaching its lowermost position.

For releasably holding the back in the different positions, I provide the following described mechanism.

A rock member 15, which is provided with 85 a U-shaped crank portion 16, extends through and is pivotally mounted in the rear legs 3, as is best shown in Fig. 2.

The rock member 15 is provided with rearwardly extending ends, which are adapted 90 to be depressed by the operator's foot, for the purpose of swinging upwardly the crank 16.

Secured respectively to the arms 14 are two catch plates 17, each provided with a 95 notch 18 in the upper edge thereof, said notches being adapted to receive the crank 16, when the back is swung to the upright position, as shown in Fig. 3.

Vertical U-shaped guides 19 are secured 100 to the inner sides respectively of the legs 3 and have slidably mounted therein respectively the arms of the crank 16.

Pivoted at their upper ends to the bottom of the frame 1 near opposite sides thereof 105 are two curved bars 20, the convex lower

edges of which are provided each with ratchet teeth 21, which are adapted to engage with a horizontal bar 22, the ends of which are respectively secured to the 5 arms 14.

Two links 23 are pivoted at one set of ends to the lower ends of the bars 20, and at their other set of ends are pivoted to the horizontal portion of the crank 16.

10 By depressing the rear ends of the rock member 15, the crank 16 may be raised, thereby lifting the lower ends of the bars 20, through the intermediacy of the links 23, so that said teeth 21 will clear the rod 22, so as to permit the back to be swung to the lowermost position.

15 When in the lowermost position, the back may be swung upwardly without depressing the rear ends of the rock member 15.

20 When the back is in the upright position, shown in Fig. 3, and the rear ends of the rock member 15 are depressed, the crank 16 will be lifted out of the notches 18, thereby releasing the back so that it may be swung 25 downwardly.

25 Pivoted to the frame 1 is a foot rest 24 which is adapted to be swung from the vertical position shown in Fig. 3 to the horizontal position shown in Fig. 4. For swinging the foot rest 24 to and holding it in the horizontal position, it has secured to it pivotally the upper ends of two brace members 25, the lower ends of which are respectively pivoted by a transverse rod 26 to the upper 30 ends of two brace members 27, the lower ends of which are respectively pivoted to the front legs 2.

35 Two links 28 have their opposite ends respectively pivoted to the rods 22 and 26.

40 When the back is swung from the upright position to the horizontal position shown in Fig. 4, the links 28 will force the brace members 25 and 27 into longitudinal alinement with each other, thereby forcing the foot rest 24 into and holding it in the horizontal 45 position shown in Fig. 4.

50 When the back is swung to the horizontal position, if desired, the arms 5 may be also swung to the horizontal position, and if desired, to a depending position, if the hinges 55 6 are constructed so as to permit them so to do.

55 For releasably holding the arms 5 in the upright position shown in Fig. 1, the frame 8 has pivoted to opposite edges thereof two

latches 29 which are adapted automatically to engage and hold the arms 5 respectively, when said arms and the back are swung to the upright position shown in Fig. 1.

60 I do not limit my invention to the structure shown and described, as modifications, within the scope of the appended claims, may be made without departing from the spirit of my invention.

Having thus described my invention, what 65 I claim and desire to secure by Letters Patent, is:—

1. A chair comprising a seat having legs, a back pivoted to said seat, a rock member extending transversely across the chair and pivoted in opposite rear legs thereof and provided with a crank and arranged to be operated from either side of the chair, and means carried by the back and adapted to releasably engage said crank for holding 75 the back in the upright position.

2. A chair comprising a seat having legs, a back pivoted to said seat, a rock member extending transversely across the chair and pivoted in opposite rear legs thereof and provided with a crank and arranged to be operated from either side of the chair, a toothed member pivoted to said seat, a link connecting the crank and said toothed member, and means carried by the back and 80 adapted to releasably engage said toothed member for holding the back in different positions.

3. A chair comprising a seat having legs, a back pivoted to said seat, a rock member 90 extending transversely across the chair and pivoted in opposite rear legs thereof and provided with a crank and arranged to be operated from either side of the chair, a toothed member pivoted to said seat, a link 95 connecting the crank and said toothed member, means carried by the back adapted to releasably engage said toothed member for holding the back in different positions, and means carried by the back adapted to releasably engage said crank for holding the back in the upright position.

100 In testimony whereof I have signed my name to this specification in presence of two subscribing witnesses.

ISRAEL V. MYERS.
